UNITED STATES PATENT OFFICE.

WILLIAM G. HURLBERT, OF WARREN, OHIO.

CORNER BEAD OR STRIP.

SPECIFICATION forming part of Letters Patent No. 780,344, dated January 17, 1905.

Application filed April 4, 1904. Serial No. 201,583.

To all whom it may concern:

Be it known that I, WILLIAM G. HURLBERT, of Warren, in the county of Trumbull and State of Ohio, have invented certain new and useful Improvements in Corner Beads or Strips; and I do hereby declare the following to be a full, clear, and exact description of the invention, such as will enable others skilled in the art to which it appertains to make and

10 use the same.

This invention relates to that class of corner beads or strips having clips designed to be secured directly to a wall and provided with means for retaining the bead in position.

15 The object of the invention is to provide an improved form of bead and clip whereby the latter, while capable of rigidly holding the bead, may yet be readily adjusted longitudinally of the latter.

20 In the accompanying drawings, Figure 1 is a view in perspective of a bead and clip constructed in accordance with my invention. Fig. 2 is a sectional view showing the device secured to the angle of a wall. Fig. 3 shows 25 the clip and a portion of the bead out of engagement.

Referring to the drawings, 1 designates a corner bead or strip, preferably of metal, designed to be positioned at the angle of a wall 30 and to project such distance from the corner that the plaster may be applied flush with its edge, whereby the finished surface will have a firm seat and not be readily broken or cracked at its exposed corner. The bead or strip is 35 shown as consisting of a single piece of metal bent at its longitudinal center approximately in the form of a bowed spring to form a circular trough or channel 2, the outer contour of which forms the bead proper and divergent 40 side walls 3, terminating in lateral flanges 4. The walls are provided, as usual, with holes or perforations to accommodate the plaster.

45 5 designates the clip. This is shown as consisting of a single metallic plate bent back upon itself to provide engaging arms or members 6, having holes or perforations 7, by which the clip is secured to a wall or joist. At the point at which it is bent upon itself the plate is formed in the shape of a bowed spring and a 50 circular portion 8 thus provided, designed to

be accommodated by the circular trough or channel 2 of the bead 1. After forming the bowed spring the arms 6 of the plate are brought close together, as at 9, and then bent divergently. A clip thus made will securely 55 retain the bead, but may readily be adjusted longitudinally to any point of the latter or removed therefrom by pressing the arms 6 together to overcome the tension of the spring. When the clip is positioned in the bead, its 60 arms 6 are normally bearing outwardly against the walls 3, adjacent the trough or channel 2. Thus it will be seen that the two elements have substantially a spring action which insures their positive engagement, but which 65 permits of ready adjustment.

The advantage of my invention is that the construction of the article is simplified and its cost of manufacture lessened, at the same time providing means for positively holding 70 the bead and yet permitting the clip to be adjusted to any desired point.

I claim as my invention—

1. The combination with a corner strip or bead having two corresponding divergent side 75 walls and an intermediate trough or channel, of a clip movable within the space between said walls longitudinally thereof and having a bowed portion designed to be accommodated by said trough or channel and normally held 80 therein by frictional engagement, for the purpose stated.

2. The combination with a strip or bead consisting of a single piece of metal bent to form substantially a bowed spring and corresponding side walls, of a clip consisting of a single piece of metal bent to form a bowed spring and corresponding side arms, the bowed portion of said clip being designed to be accommodated within the bowed portion of said 90 bead and normally held therein by frictional engagement, said clip being movable longitudinally of the bead.

3. As an article of manufacture a corner-protecting device for walls, comprising a bead 95 or strip formed of a single piece of metal bent back upon itself to provide a trough or channel and two divergent side walls and flanges at the free ends of such side walls, and a clip designed to be secured to a wall formed of a 100

single piece of metal bent back upon itself to form two corresponding arms and a bowed portion designed to fit in and capable of being moved longitudinally of said trough or 5 channel wherein it is normally held by frictional engagement.

In testimony whereof I have signed this

specification in the presence of two subscribing witnesses.

WILLIAM G. HURLBERT.
